UNITED STATES PATENT OFFICE

113,731

DESIGN FOR A LOWER BOWL FOR A COFFEE BREWER

Harvey Cory, Chicago, Ill.

Application January 23, 1939, Serial No. 82,536

Term of patent 7 years

To all whom it may concern:

Be it known that I, Harvey Cory, a citizen of the United States, residing at Chicago, in the county of Cook and State of Illinois, have invented a new, original, and ornamental Design for a Lower Bowl for a Coffee Brewer, of which the following is a specification, reference being had to the accompanying drawing, forming a part thereof, wherein

I claim:

The ornamental design for a lower bowl for a coffee brewer, as shown and described.

HARVEY CORY.
